KNOB STRUCTURE FOR LOCKS

Henry G. Voight, New Haven, Conn., assignor to
Sargent & Company, New Haven, Conn., a corporation of Connecticut

Application November 18, 1933, Serial No. 698,625

2 Claims. (Cl. 292—347)

This invention relates to door knobs and more particularly to an improved and novel construction in a sheet metal door knob which will provide a simple structure which may be economically manufactured and at the same time be easily assembled with other parts of the door lock or latch casing with which the knob is to be used.

In the past, sheet metal door knobs have been provided in some instances, and in order to secure such knobs to the usual spindle of the door lock, they have been provided with a cast metal core or sleeve provided with a square opening, this core or sleeve being entirely within the sheet metal shank portion of the knob. Such knobs are secured in place by a screw which passes through the shank of the knob and the cast metal sleeve into the spindle.

In the present construction it is desired to secure the knob shank in place by a different means, such as by a clip or anchor member secured to some part of the lock case and projecting into a groove in the knob shank. For this purpose I have provided a knob shank of novel construction, such that while the knob and greater part of the shank can be made of sheet metal, the part of the shank containing the groove can be made as a screw machine product and readily secured to the sheet metal portion of the shank so that an economical and efficient structure is provided.

One object of the invention is the provision of a door knob and knob shank of novel and improved construction.

A further object of the invention is the provision of a door knob constructed principally of sheet metal but provided with an end portion of heavier material, such that it may suitably engage a lock spindle and at the same time be rotatably secured to the case of the lock.

To these and other ends, the invention consists in the novel features and combinations of parts to be hereinafter described and claimed.

In the drawing:

Fig. 1 is a sectional view through a door showing a lock mounted on the door having my improved knobs connected thereto;

Fig. 2 is a sectional view of the knob structure;

Fig. 3 is an elevational view of the thimble or shank extension secured to the sheet metal portion of the knob; and

Fig. 4 is an end view of the elements shown in Fig. 3.

To show a preferred embodiment of my invention, I have shown a lock having a case 10

mounted upon a door 11, the lock being provided with the usual knobs 12 having knob shanks 13 wherein is provided a groove 14 to receive the end of an anchor member 15 secured to the lock case by the screw 16. This groove 14 extends peripherally about the knob shank so that the knob will be rotatably secured to the lock case but will be held against longitudinal movement with respect thereto.

The knob 12 is preferably made of sheet metal, as is also the part 17 of the knob shank, which has been designated as a whole by the numeral 13. This portion 17 of the shank is, as shown in Fig. 2, flared at the end adjacent the knob 12 and the metal displaced so as to provide a peripheral groove 18 in which may be inserted and gripped the edge 19 of the knob 12 so as to secure the knob to the portion 17 of the shank.

The knob shank, designated generally by the numeral 13, comprises the part 17 which has already been described, and the thimble or extension 20 which is secured to the end of the portion 17 of the shank to project therefrom. This thimble comprises a member generally of cylindrical shape and provided intermediate its ends 20 with the peripheral groove 14. At one side of this groove the member 20 is somewhat reduced in size, the reduced portion terminating in a shoulder 21, and the surface of the reduced portion being knurled or provided with longitudinally 30 extending ribs, as shown at 22. The interior of the thimble or extension 20 is bored out, as shown at 23, leaving a bottom wall 24 at one end, in which is stamped a non-circular opening 25 which, as will be understood, is adapted to receive 35 a correspondingly shaped spindle, shown in Fig. 1 in dotted lines as at 26.

The thimble 20 may be readily and conveniently secured to the knob shank 17 by having the reduced knurled portion 22 forced into the open 40 end of the shank as far as is permitted by the shoulder 21. It will be understood that this portion of the thimble is slightly larger than the internal diameter of the shank so that when the thimble is forced into the shank, the knurled portion will bite into the metal of the shank and provide a firm and secure connection between the two parts.

The thimble 20 may readily be made as a screw machine product and the groove 14 milled in the 50 periphery thereof. This method of manufacture provides a groove having sharply defined walls and of constant dimensions throughout its extent so that the knob when secured to the door casing will be properly held in place by the anchor 55

member 15. If it were attempted to spin a groove in the sheet metal portion of the knob, such a groove would not possess the advantageous characteristics just described of the milled groove 14.

5 While I have shown and described a preferred embodiment of my invention, it will be understood that it is not to be limited to all of the details shown, but is capable of modification and variation within the spirit of the invention and
10 within the scope of the appended claims.

What I claim is:

1. A door knob having a sheet metal shank portion projecting therefrom, an extension member of material heavier than the shank secured to the end thereof, said member being cup-shaped in form, having a bottom wall with a non-circular opening therein, and having a reduced portion

adjacent its open end providing an exterior shoulder, and said shank being forced over the reduced portion of said extension member to abut said shoulder.

2. A door knob having a sheet metal shank portion projecting therefrom, an extension member of material heavier than the shank secured to the end thereof, said member being cup-shaped in form, having a bottom wall with a non-circular opening therein, and having a reduced portion adjacent its open end providing an exterior shoulder, said shank being forced over the reduced portion of said extension member to abut said shoulder, and said member having an exterior groove formed thereon beyond said shoulder on the side thereof opposite the end of the shank. 15

HENRY G. VOIGHT.
